(57) **CLAIM**

The ornamental design for a portable electric sander body, as shown and described.

DESCRIPTION

FIG. 1 is a front, left and top perspective view of a portable electric sander body showing our new design;

FIG. 2 is a rear, right and top perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof;

FIG. 8 is a right side elevational view thereof; and,

FIG. 9 is a front, left and top perspective view of the portable electric sander body in accordance with our new design illustrating a state in which an environmental structure (a battery) is attached to the portable electric sander body. The broken lines in the drawings illustrate the environmental structures or portions of the portable electric sander body which form no part of the claimed design.
